AUTOMATIC STROKE-CHANGING APPARATUS FOR WINDMILLS

Wilfred B. Crofton, Johannesburg, Transvaal,
Union of South Africa

Application October 27, 1952, Serial No. 317,064

8 Claims. (Cl. 74—110)

This invention relates to windmill driven pumps and provides a device for halving the stroke and load on the windmill when the wind loses velocity, whereby the wheel may be kept turning while pumping water at a reduced rate.

According to the invention a device for the purpose described comprises a pair of toothed racks reciprocable in fixed parallel guides and in toothed engagement on opposite sides of a pinion rotationally mounted on a member reciprocable between and parallel with the racks, a connection between one of the racks and the windmill pitman or the like for reciprocation of said rack under rotation of the windwheel, a connection between the pinion mounting member and the pump rod, and means for automatically coupling and uncoupling the said rack and the said member for respectively transmitting the full stroke or half stroke to the pump rod according to the speed at which the first mentioned rack is reciprocated by the windmill.

The invention also consists in a device according to the preceding paragraph wherein the said coupling and uncoupling are effected automatically through the agency of a member freely hung from the pitman-connected rack so as to rise and fall through the full stroke, which member, each down stroke, strikes a fixed abutment on the rack guide system and is swung through an arc which depends upon the speed of the stroke, the arrangement being such that when the speed and the arc of swing of said member diminishes to a certain degree the said member comes into operative engagement with trip mechanism to effect the said uncoupling and divide the stroke between the two racks through the pinion.

The principles of operation of a device according to the present invention will be understood from the following general description leading to the description of a preferred construction of the apparatus with reference to drawings accompanying this specification.

The device may comprise in general two toothed racks, one pinion between them, and guide means in which the racks slide, together with levers, springs, bolts and cross-heads, as described hereunder.

The guide system in which the racks slide is formed by two channel irons joined top and bottom; spaced so that when the pinion gear is meshed into and between the toothed racks the assembly can slide freely up and down the full stroke of the windmill.

The pinion revolves in a cage which slides between the edges of the channels. This cage is attached to the pump rod. The windmill pitman or the equivalent is attached to one of the racks in a connection which slides above the pinion cage.

The second rack is free to move up and down when the pinion cage and the first rack are locked together, and the whole assembly can rise and fall the full stroke of the windmill.

When the said parts are unlocked however, the pitman connection draws its rack up, rolling the pinion with its cage and pump rod up the opposite rack, thus halving

2

the stroke of the pump rod and halving the quantity of water pumped per stroke; whereby half the velocity of wind keeps the wheel turning.

The method of locking and unlocking the parts aforesaid automatically may be as follows: The pitman connected rack has a rod fixed to it which projects across the outside of the channel enclosing the free rack; a square rod hangs on this bar; a projection on this bar strikes a projection or cam fixed to the outside of the channel casing and as the bar rises and falls it swings in an arc which is regulated by the strength of the blow, or in other words, by the speed of the windmill.

The lock which couples the pinion cage and the first-mentioned rack is similar to the ordinary door spring lock, such as the Yale, the latch pin sliding in the lower pinion cage and the latch cavity being provided in the pitman rack connection.

A T-shaped lever is pivoted horizontally on the pinion cage at the junction of the cross bar of the T. The long arm of this lever projects over the inside edge of the channel. The upper arm operates the latch pin and the lower arm operates a similar sliding pin at the bottom of the lower crosshead.

Both pins may be composed of half inch square steel bar. A tension spring keeps the T lever normally in the position where the long arm is sloping downwards; the upper arm is holding the latch pin in locked position (but not necessarily locked) and the lower arm in unlocked position. Two light springs tend to keep both latch pins in unlocked position so that when the T lever pressure is removed the latch pins slip back to unlocked position.

A stop lever or arm is pivoted at a point at the lower end of the channel guide system in such a way that when it is moved inwards the long arm of the T lever meets it on the downstroke which causes the long arm of the lever to move upwards relative to the pinion cage, thus pressing the lower pin inwards and removing the inward pressure on the locking latch pin; the lower pin then comes to rest on a fixed seat attached to the channel case. This action removes the weight of the pump rod from the top latch pin and allows it to fly back and unlock itself without jar.

The moment the pinion cage lifts, the lower pin, which might be styled a spacing pin, flies back and leaves a space between the bottom of the cage and the fixed seat. Thus, when pumping normally on full stroke, the weight of the pump rod hangs permanently on the assembly without striking any part of the case at the bottom of the stroke. Only when running on half stroke or actually locking or unlocking at the bottom of the stroke does the pinion cage actually rest on the seat or base.

When changing from full stroke to half stroke the locking latch pin itself, being shaped like a ramp similar to an ordinary door lock, pushes the T lever across, thus sliding the spacing pin across before it reaches the rest seat or base.

When the pinion cage comes to rest on this pin on the rest seat, the weight of the pump rod is removed from the upper latch pin, it slides back into unlocked position and the pinion cage is lifted at half stroke, as before described.

To fit this machine to a windmill it is only necessary to fix a wooden beam across the windmill tower and hang the stroke change device on the beam in line with the pump rod and pitman with the stroke change at the bottom of the stroke, and connect the windmill pitman to the top crosshead and the pump rod to the bottom crosshead with the windmill at bottom dead centre and the pump at the bottom of the stroke.

The base of the channel guide system may be used as a sump to retain oil and the rack or racks rising and

falling will keep the entire mechanism lubricated. Obviously, weights may be used instead of springs subject to their not adding unduly to the weight and cost of the apparatus.

An improved and preferred embodiment of the invention is shown in the accompanying drawings, wherein:

Figure 1 is a side elevation showing the parts coupled for full stroke direct drive of the pump rod from the windmill pitman or the like;

Figure 2 is a sectional elevation showing the rack and pinion arrangement, with the parts uncoupled except through the driving rack and the pinion for half-stroke operation;

Figure 3 is a cross-section on the line III—III of Figure 1; and

Figure 4 is a fragmentary lower-end elevation corresponding to the lower parts of Figure 1 but with the locking mechanism tripped at the bottom of a slow-speed stroke to uncouple or prevent recoupling of the pitman or the like and the pinion-mounting member with which the pump rod is connected.

In these drawings the racks 1 and 2 are slidable together or in reverse directions in guides provided by the two parallel opposed channels 3 and 4 which are cross-connected at their top and bottom ends, and the pinion 5, engaging with the racks, is rotatable on its shaft 6 which is mounted in a cage 7 slidable under guidance from the opposed margins 3' and 4' of the channels.

The connection at 8 between the windmill and the rack 1 is in an integral head portion 1' of the rack casting, and the pump rod 9 is connected at 10 to the base of the cage 7, the rod passing downwardly through a central aperture in the floor of the channel assembly.

The mechanism for coupling the rack 1 directly to the pinion cage 7 consists of a U-shaped latch 12 pivotally connected to the cage via the ends of the pinion shaft 6, which latch may fit into a recess 13 formed in the rack head, to couple the parts as shown in Figure 1.

The latch is urged normally into its upright position (see Figure 2) by an arm 14 (see Figures 1 and 3) against a stop 15 on the pinion cage 7, the tail 14' of the arm being loaded upwardly by the tail 16' of a further arm 16 pivoted at 17 to the side of the cage, the opposite extremity 16'' of which arm 16 is biased by a tension spring 18 anchored by a bracket 19 also to the cage. Biased thus the latch 12 will tend to enter and remain in the recess 13, being guided into position by the ramp surface 13' which first engages the top of the latch when the rack 1 runs down the guides past the pinion cage.

Referring to Figure 1, with the parts coupled as there shown for full stroke working, a further arm 20 is pivoted at 20' to the side of the channel 3 and is loaded by a system of compression springs 21 and guide rods 21' outwardly into engagement with an abutment plate 22 attached to the same channel, and by shaping the arm 20 and the plate 22 as shown a throat 23 is defined between them when they are in contact.

From a bracket 24 projecting sidewise from the head 1' of the rack 1, a member 25 is freely suspended on a transversely arranged pivot pin 26, the lower and free end 25' of the member 25 being pointed and capable, when the rack 1 is lowered slowly, of being driven into the throat 23 aforesaid as the bottom end of the full pumping stroke is being approached. As a result of this action, when it is permitted to occur, the arm 20 is forced over against its spring system 21, 21' into the position shown in Figure 4, thereby presenting an abutment 20' in the downward path of the end 16'' of the spring loaded arm 16. On the parts meeting, the arm 16 is rocked into the position shown, thereby relieving the erecting force through the arm 14 on the latch, which under the action of a weighted lever 27 is withdrawn from the recess 13 in the rack head, the parts being thus uncoupled.

So long as the speed of operation is low enough for the member 25 to function as explained, at the lower end of the stroke, the latch is prevented from coupling the pump rod to the pitman drive rack 1.

Adverting now to the operation of the swinging member 25 at normal or high speeds when full stroke functioning is required, a fixed abutment 28 on the channel 3 is so positioned as to lie in the path of a projection 29 fixed on the member 25, as the latter is lowered with the rack head 1', and thereby as the lower end of each stroke is approached to receive a knock swinging the member 25 outwardly (in relation to the plane of the drawings) through an arc which increases with the speed of the windmill and is ordinarily so great that the pointed end 25' of the member 25 is prevented from entering the throat 23 aforesaid. In thus working the latch mechanism already described is not tripped at the normal or higher speeds but only when the speed drops to a value so low that half-stroke working is required to keep the pump in operation, in which condition the mechanism will continue to be tripped at the end of each downward stroke to prevent relocking of the latch and coupling of the pitman or the like in effect directly to the pump rod.

Additionally the arm 20 is arranged in being moved into the position shown in Figure 4 to push a slide 30 across the floor 11 of the channel guide system into the position shown in Figure 2, i. e. below the lower end of the free rack 2 whereby to take the weight of the pump rod (through the pinion cage) at the bottom of each stroke, thus relieving the load on the latch for free movement of the latter into unlocked position in conditions when the member 25 is operative.

What I claim is:

1. An automatic stroke changing device for coupling a reciprocable driven member to a reciprocating driving member, comprising fixed parallel guides, a pair of toothed racks reciprocable in said guides and disposed with their toothed sides facing and spaced from one another, a cage reciprocable parallel to said racks, a pinion rotatably mounted in said cage and meshing with both of said racks, driving connection between said driving member and one of said racks, herein designated the driven rack, the other of said racks, being freely reciprocable within fixed limits, a stop for limiting the movement of said other rack, driving connections between said cage and said driven member, means for releasably coupling said cage to said driven rack so that both racks and said cage reciprocate together and means responsive to the speed of reciprocation of the driving member for uncoupling said cage from the driven rack when said speed drops below a predetermined value so that the pinion is driven by the driven rack, the other rack being held stationary at one limit of its movement by said stop, and the cage is thereby driven by said pinion at half the speed and through half the stroke of said driven rack.

2. An automatic stroke changing device for coupling a reciprocable driven member to a reciprocating driving member, comprising fixed parallel guides, a pair of toothed racks reciprocable in said guides and disposed with their toothed sides facing and spaced from one another, a cage reciprocable parallel to said racks, a pinion rotatably mounted in said cage and meshing with both of said racks, driving connection between said driving member and one of said racks, herein designated the driven rack, the other of said racks being freely reciprocable within limits, a stop for limiting the movement of said other rack, driving connections between said cage and said driven member, latch means for releasably coupling said cage to said driven rack so that both racks and said cage reciprocate together, said latch means being movable between a latched position and an unlatched position, trip means for moving said latch to an unlatched position to uncouple said cage from said driven rack so that said pinion is driven by said driven rack, the other rack being held stationary by said stop, and the cage is thereby moved by said pinion at half the speed and

through half the stroke of the driven rack, said trip means comprising a trip member swingably carried by said driven rack and biased to a rest position in which it is effective to release said latch means, and a fixed deflecting member positioned to engage said trip member as said driven rack reciprocates and thereby swing said trip member from said rest position through an arc the amplitude of which varies with the speed of movement of said driven rack.

3. An automatic stroke changing device for coupling a reciprocable driven member to a reciprocating driving member, comprising fixed parallel guides, a pair of toothed racks reciprocable in said guides and disposed with their toothed sides facing and spaced from one another, a cage reciprocable parallel to said racks, a pinion rotatably mounted in said cage and meshing with both of said racks, driving connection between said driving member and one of said racks, herein designated the driven rack, the other of said racks being freely reciprocable within limits, a stop for limiting the movement of said other rack, driving connections between said cage and said driven member, an abutment on said driven rack, a latch pivotally mounted on said cage and swingable from a released position to a latched position in which it engages said abutment to couple said cage to the driven rack so that both racks and said cage reciprocate together, and trip means for swinging said latch to released position at the end of a stroke to uncouple said cage from said driven rack so that said pinion is driven by said driven rack, the other rack being held stationary by said stop, and the cage is thereby moved by said pinion at half the speed and through half the stroke of the driven rack.

4. A device according to claim 3, in which said trip means comprises a trip member swingably carried by the driven rack and biased to a rest position in which it is effective to release said latch, and a stationary deflecting member positioned to engage said trip member as said driven rack reciprocated and thereby swing said trip member from said rest position through an arc the amplitude of which increases with increase of speed of said driven rack.

5. An automatic stroke changing device for coupling a reciprocable driven member to a reciprocating driving member, comprising fixed parallel guides, a pair of toothed racks reciprocable in said guides and disposed with their toothed sides facing and spaced from one another, a cage reciprocable parallel to said racks, a pinion rotatably mounted in said cage and meshing with both of said racks, driving connection between said driving member and one of said racks, herein designated the driven rack, the other of said racks being freely reciprocable within limits, a stop for limiting the movement of said other rack, driving connections between said cage and said driven member, an abutment on said driven rack, a latch pivotally mounted on said cage and swingable from a released position to a latched position in which it engages said abutment to couple said cage to the driven rack so that both racks and said cage reciprocate together, means for biasing said latch to latched position, and trip means for swinging said latch to released position at the end of a stroke to uncouple said cage from said driven rack so that said pinion is driven by said driven rack, the other rack being held stationary by said stop, and the cage is thereby moved by said pinion at half the speed and through half the stroke of the driven rack, said trip means comprising an arm pivoted on said guides, a stationary cam surface, means for swinging said arm toward said cam surface to an inactive position, a swingable trip member pivotally carried by said driven rack and biased to a rest position in which it comes between said arm and said cam surface as the driven rack approaches the end of a stroke and thereby swings said arm to an active position, operative connections between said arm and said latch

to release said latch when said arm is in active position, and a stationary deflecting member positioned to engage said trip member as said driven rack reciprocates and thereby swing said trip member from said rest position through an arc the amplitude of which increases with increase of speed of said driven rack, said arm and cam surface being so positioned that when said trip member is swung a predetermined amount it does not come between them.

6. An automatic stroke changing device for coupling a vertically reciprocable pump rod to a vertically reciprocating driving member, a pair of vertically reciprocable parallel racks disposed with their toothed sides facing and spaced from one another, means for guiding said racks, a cage reciprocable parallel to said racks, a pinion rotatably mounted in said cage and meshing with both of said racks, means for connecting one of said racks, herein designated the driven rack, with the driving member, the other of said racks being freely reciprocable within limits, a stop for limiting the movement of said other rack, means for connecting said cage to the pump rod, means for releasably coupling said cage to said driven rack so that both racks and said cage reciprocate together, means responsive to the speed of reciprocation of the driven rack for uncoupling said cage from the driven rack when said speed drops below a predetermined value so that the pinion is driven by said driven rack, the other rack being held stationary by said stop and the cage is thereby driven by said pinion, and means for temporarily supporting said pump rod at the lower end of its stroke to relieve said coupling means of the load of said rod and thereby facilitate its release.

7. An automatic stroke changing device for coupling a vertically reciprocable pump rod to a vertically reciprocating driving member, a pair of vertically reciprocable parallel racks disposed with their toothed sides facing and spaced from one another, means for guiding said racks, a cage reciprocable parallel to said racks, a pinion rotatably mounted in said cage and meshing with both of said racks, means for connecting one of said racks, herein designated the driven rack, with the driving member, the other of said racks being freely reciprocable within limits, a stop for limiting the movement of said other rack, means for connecting said cage to the pump rod, latch means for releasably coupling said cage to said driven rack so that both racks and the cage reciprocate together, said latch means being movable between a latched and an unlatched position, trip means for moving said latch means to unlatched position at the end of a downward stroke of said driven rack to uncouple said cage from said driven rack so that said pinion is driven by said driven rack, the other rack being held stationary by said trip, and the cage is thereby moved by said pinion, said trip means comprising an inertia operated trip member carried by said driven rack.

8. A stroke changing device for coupling a vertically reciprocable pump rod to a vertically reciprocable driving member, a pair of vertically reciprocable parallel racks disposed with their toothed sides facing and spaced from one another, a cage reciprocable parallel to said racks, a pinion rotatably mounted in said cage and meshing with both of said racks, means for connecting one of said racks, herein designated the driven rack, with the driving member, the other of said racks being freely reciprocable within limits, a stop for limiting the movement of said other rack, means for connecting said cage to the pump rod, means for releasably coupling said cage to said driven rack so that both racks and the cage reciprocate together and means for releasing said coupling means so that said driven rack drives said pinion, the other rack being held stationary by said stop, and the cage is thereby moved by the pinion at half the speed and through half the stroke of said driven rack.
